UNITED STATES PATENT OFFICE.

JOSEPH N. WIGGIN, OF EAST ORANGE, NEW JERSEY, ASSIGNOR TO H. B. WIGGIN'S SONS COMPANY, OF BLOOMFIELD, NEW JERSEY, A CORPORATION OF NEW JERSEY.

DESIGN FOR A WALL OR BOOK COVERING.

41,865.

Specification for Design.

Patented Oct. 24, 1911.

Application filed February 4, 1911. Serial No. 606,652. Term of patent 14 years.

To all whom it may concern:

Be it known that I, JOSEPH N. WIGGIN, a citizen of the United States, residing at East Orange, in the county of Essex and State of New Jersey, have invented a new, original, and ornamental Design for Wall or Book Coverings, of which the following is a specification, reference being had to the accompanying drawings, forming a part thereof, in which—

The figure is a plan view of a portion of a wall or book covering showing my design.

I claim—

The ornamental design for a wall or book covering, as shown.

JOSEPH N. WIGGIN.

Witnesses:

M. MERKLE,
G. B. PRINDLE.
